(57) **CLAIM**

The ornamental design for a toner cartridge, as shown.

DESCRIPTION

FIG. 1 is a left-front-top perspective view of the toner cartridge of the present invention, showing a new design; FIG. 2 is a front elevational view thereof;

FIG. 3 is a back elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a right-back-bottom perspective view.

The broken lines in the figures show portions of the toner cartridge that form no part of the claimed design. The shade lines in the figures show contour and not surface ornamentation.

1 Claim, 6 Drawing Sheets
